UNITED STATES PATENT OFFICE.

HARRY C. JOHANSEN, OF CHICAGO, ILLINOIS, ASSIGNOR TO SULLIVAN MACHINERY COMPANY, A CORPORATION OF MASSACHUSETTS.

CLAMPING MECHANISM.

1,399,261.

Specification of Letters Patent.

Patented Dec. 6, 1921.

Application filed November 13, 1918. Serial No. 262,294.

To all whom it may concern:

Be it known that I, HARRY C. JOHANSEN, a citizen of the United States, residing at Chicago, in the county of Cook and State of Illinois, have invented certain new and useful Improvements in Clamping Mechanism, of which the following is a full, clear, and exact specification.

This invention relates to clamping mechanism, and more particularly to a clamping mechanism such as is commonly used on drill sharpeners for holding the work (for example, a drill steel) during the upsetting operation.

The object of the present invention is to provide an improved clamp operating means and one in which the clamping movement of the elements thereof does not force some of these elements into a frictional engagement which will cause the mechanism to operate slowly and jerkily and which will absorb a great part of the available power for operating the clamp. A further object of the invention is to provide an improved mechanical connection between the driving and driven elements of the clamping mechanism, whereby the movement of a part of these elements does not tend to force other of the elements out of their proper alignment, and so avoids the multiplication of the stresses which tend to bend or break the elements, and permits the use of a lighter, more rapidly acting machine. These and other objects and advantages of my improvement will, however, hereinafter more fully appear.

In the accompanying drawings I have shown for purposes of illustration one form which my invention may assume in practice.

In these drawings,—

Figure 1 is a side elevation of a drill sharpener provided with my improved clamping mechanism, a part thereof being broken away to show the clamp operating means.

Fig. 2 is a sectional view of the clamp operating means taken on the line 2—2 of Fig. 1.

Fig. 3 is a sectional view on the line 3—3 of Fig. 1 with portions of the clamp actuating means shown in elevation for clearness.

Fig. 4 is a side elevation of the toggle joint shown in Fig. 1, these parts being in 55 different positions.

In this illustrative construction I have shown a drill sharpener 1 having a vertically disposed swaging hammer 2 adapted to operate the upper of two swaging dies 3, the fluid pressure for operating this hammer being supplied from the main supply pipe 4 by a pipe (not shown) which may pass through the base of the sharpener or around it. The flow of pressure fluid to the 65 swaging hammer 2 is controlled by a foot lever 5 which operates a valve in the pipe line, above mentioned, the valve and pipe line in the preferred construction being placed within the base of the drill sharpener, the latter being supplied with a removable plate 6 to facilitate the installation and inspection of these and other parts that will hereinafter be described.

A pneumatic pinning tool and tool operating mechanism 7 is mounted on the sharpener on or about the level of the swaging dies, the fluid pressure for operating this tool being supplied through pipes 8 and 9. No lever or valve means are shown for controlling the operation of this pinning tool, the tool being set in operation by pressing the work against it and being stopped by the withdrawal of the work therefrom.

A horizontal pneumatic hammer 10 operates a dolly 10' to upset the end of a drill steel which is held between two clamping jaws 11 and 12. A pipe 13 supplies pressure fluid to this hammer, and an exhaust pipe 14 conducts the exhaust therefrom to 90 the working parts of the clamping mechanism, the upsetting mechanism, and the swaging mechanism, to lubricate these parts and keep them free from dust or scale. The exhaust from the swaging hammer may be 95 added to that of the upsetting hammer to increase this lubricating and cleaning action. A single lubricator 15 supplies lubricant to all the working parts, the lubricant being fed slowly to the pressure fluid and carried 100 by the latter to all parts of the apparatus. A single lever 16 controls the upsetting hammer and the clamping device (to be herein-after described) in such a manner that the clamping device is always operated to grip 105 the steel before the upsetting hammer is set

in operation. As the parts so far described form no part of the present invention, further description of these parts or their operation is thought unnecessary.

5 The upper clamping jaw 11 is mounted in a yoke carried on the upper end of two parallel standards 17, the latter being so mounted in the frame of the drill sharpener that they have a limited reciprocating movement therein. The lower ends of these standards are fixedly mounted in spaced relation in a second yoke 18. Two oppositely disposed bearings 19 and 20 are respectively mounted on the drill sharpener frame and 10 the upper face of the yoke 18 in such a manner that they receive the thrust of a toggle joint mechanism comprising two links 21, 22 pivotally connected to the frame and yoke 18 at points adjacent the two bearings 15 mounted thereon, and pivotally connected to each other by a pin 23 passing through the overlapping ends of these links and two guide blocks 24.

Coöoperating with the toggle mechanism 25 just described, and adapted to move in a direction substantially at right angles to the direction of movement of the standards, is a plunger 25 provided with two oppositely disposed pistons 26, 27, the latter carrying 30 piston heads 28, 29 having differential areas. These pistons reciprocate in two oppositely disposed cylinders 30, 31, the larger cylinder being supplied with pressure fluid through a pipe 32, a valve box 33, and a port 34, while the smaller cylinder is always supplied with pressure fluid under initial pressure through a pipe 35 and port 36. By this construction it will be noted that the movement of the plunger is governed by 35 the pressure of the fluid admitted to the cylinder 30 and that a simple valve member may be provided in the valve box 33 and operated by a suitable connection with the lever 16 to admit fluid pressure to but one 40 end of one cylinder and to exhaust the fluid therefrom. In order that the fluid flow to the hammer 9 may be properly timed with the flow to the cylinder 30 so that the clamping mechanism is always set on the work during the upsetting operation, the pipe 13 is connected to the valve box 33, and the flow through this pipe is governed preferably by the same valve member that 45 controls the flow to the cylinder 30.

50 In the form of my improvement shown herein, it will be noted that by the use of the cylinder 31 the valve operating mechanism can be simplified, the time necessary for releasing the jaws from the work has 55 been reduced because the plunger will move to the left as soon as the exhaust from the cylinder 30 has been opened, and, further, that because of the sizes of the differential cylinder heads used, the force tending to

move the toggle to a set position (Fig. 1) 65 is amply sufficient for the purpose.

The plunger 25 is provided with two vertical slots 37, 38 at right angles to each other, the first extending clear through the plunger to receive the links 21, 22, and the second extending parallel to the standards 17 for but a part of the depth of the plunger and being adapted to receive the guide blocks 24 between parallel guiding faces 24'. It will be noted that by this improved 75 means for connecting the plunger and toggle mechanism, as the plunger moves to the right or left the blocks will slide in the slots 38 and bear against the guiding faces 24' on the plunger in such a manner that 80 neither the relative movement of the two links, of the links and plunger, or of the pistons in their cylinders, tends to produce a frictional engagement which will materially affect the operation. Attention is also 85 directed to the fact that there are but few moving parts, that these are made strong and substantial, and that all of the parts are easily accessible upon the removal of the 90 plate 6.

It will be noted from Figs. 1 and 4 that when the clamp is in release position the axis of the pin 23 is disposed above the axis of the pistons 26 and 27 and that as the clamp is moved toward clamping position, 95 the axis of the pin moves downward until it lies in the same horizontal plane as the axis of the pistons at the moment when the parts reach the position of Fig. 1. The desirability of this arrangement is obvious when 100 it is noted that at the instant when the greatest pressure is applied in holding the member inserted in the clamp securely, there is no force present having a component in such direction as to cause binding 105 of the pistons 26 and 27 on the walls of their cylinders. Accordingly, my mechanism moves very smoothly and without waste of power due to excessive friction of the clamp actuating mechanism in its guides. 110

While I have herein shown and described for the purpose of illustration one specific form of the invention, it is to be understood that the same is chosen for illustrative purposes only and that extensive deviations 115 may be made from the disclosed form thereof without departing from the spirit of the invention or the scope of the appended claims.

What I claim is new and desire to secure 120 by Letters Patent is:

1. In combination, a frame, work clamping mechanism thereon including a toggle link, a link actuating member, and a connection between said link and said member 125 slidable in a direction transverse to the direction of movement of the member.

2. In combination, a frame, work clamp-

ing means thereon, an actuating member, and mechanical connecting means between said clamping means and member, said connecting means having a movement of translation with respect to said member.

3. In combination, a frame, work clamping mechanism thereon including a toggle link, a link actuating member, and a sliding connection between said link and said member.

4. In combination, a frame, work clamping means thereon, an actuating member, and mechanical connecting means between said clamping means and member, said connecting means having a sliding connection with said member.

5. In combination, a frame, work clamping means thereon, an actuating member having a slot therein, and mechanical connecting means between said clamping means and actuating member and including an element slideable in said slot.

6. In combination, a frame, work clamping means thereon mounted for movement in a given plane, an actuating member, a slot formed therein substantially parallel to said plane, and mechanical connecting means between said clamping means and actuating member and including an element slideable in said slot.

7. In combination, a frame, work clamping mechanism thereon, operating means for the latter, and an actuating plunger for said operating means having a plurality of oppositely disposed differential piston heads and a connection with said operating means between said heads.

8. In combination, a frame, work clamping mechanism thereon, operating means for the latter, differential cylinders mounted on said frame, and an actuating plunger for operating said mechanism, said plunger having a plurality of oppositely disposed differential pistons mounted in said cylinders, there being a sliding connection between said operating means and said plunger at a point between the heads of the latter.

9. In combination, a frame, work clamping mechanism thereon, operating means for the latter, and piston mechanism for actuating said clamping mechanism, said piston mechanism including a plurality of oppositely disposed differential piston heads and being provided with a slot between said heads, said operating means having a sliding connection with said slot.

10. In combination, a frame, work clamping mechanism thereon, operating means for the latter, a block secured to said operating means, differential cylinders mounted on said frame and an actuating plunger for said operating means having a plurality of oppositely disposed differential pistons

mounted in said cylinders and provided with a slide for the guiding of said block.

11. In combination, a frame, work clamping means thereon, a plunger therefor comprising differential piston heads, and mechanical connecting means between said work clamping means and said plunger between its heads.

12. In combination, a frame, work clamping means thereon, a plunger therefor comprising differential piston heads, mechanical connecting means therebetween, and a mechanical connection including a toggle link between said connecting means and said clamping means.

13. In combination, a frame, work clamping means thereon, a plunger therefor comprising differential piston heads, mechanical connecting means therebetween, and a mechanical connection including a plurality of toggle links between said connecting means and said clamping means.

14. In combination, a frame, work clamping means thereon, an actuating member, a mechanical connection between said actuating member and said work clamping means comprising a pivot point on which force is applied to effect clamping movement of said work clamping means, said pivot point moving toward the axis of said actuating member during clamping operation.

15. In combination, a frame, work clamping mechanism thereon, an actuating member therefor, guiding means on the frame for said actuating member, and means including a connection between said work clamping means and said actuating member acting to decrease the pressure of said actuating member on said guiding means upon progressive movement of said actuating means toward clamping position.

16. In combination, a frame, work clamping mechanism thereon, operating means therefor, an actuating member for said operating means, the point of application of force of said actuating member to said operating means being initially spaced from the axis of said actuating member and approaching the same as the parts move toward clamping position.

17. In combination, a frame, work clamping mechanism thereon including a toggle link, a link actuating member, and a connection between said toggle link and link actuating member having provision whereby when the toggle is broken force applied to said actuating member reacts along the line of the axis of movement of said actuating member and also has a component tending to cause turning movement of said actuating member, said movement of said actuating member to straight line position of the toggle link tending to eliminate the turning moment.

18. In combination, a frame, work clamping mechanism thereon comprising a movable jaw, operating means for said movable jaw adapted to move the same in opposite directions, and an actuating plunger for said operating means having a plurality of oppositely disposed differential pistons reciprocable in a line at right angles to the line of movement of said movable jaw and 10 a connection with said operating means between said pistons.

19. In combination, a frame, a stationary jaw thereon, a movable jaw adapted to cooperate therewith, means for moving said jaw toward and away from said stationary jaw comprising a guiding yoke spaced from the movable jaw, parallel standards connecting the movable jaw and yoke, toggle mechanism comprising links pivotally connected to said yoke and frame and to each other, aligned cylinders disposed on opposite sides of the plane of said standards, pistons fitting said cylinders and having a connecting member adapted to reciprocate between 25 said standards, and operative connections between said connecting member and said toggle mechanism.

20. In combination, a frame, work clamping mechanism thereon comprising a sta-

tionary clamp jaw, a movable clamp jaw, a 30 guiding yoke spaced from said movable jaw, parallel standards connecting said movable jaw and yoke, operating means for said movable jaw comprising aligned cylinders disposed on opposite sides of the plane of 35 said standards, pistons fitting said cylinders and having a connecting member reciprocable between said standards, and means pivotally connected to said guiding yoke and operatively engaged by said connecting member for operating said movable jaw.

21. In combination, a frame, work clamping mechanism thereon comprising a movable jaw, and operating means for said movable jaw adapted to move the same in 45 opposite directions including an actuating plunger for said movable jaw having a plurality of oppositely disposed pistons and an operative connection with said jaw between said pistons, cylinders in which said pistons 50 are reciprocable, and means for supplying pressure fluid to the smaller of said pistons constantly and to the larger thereof intermittently at the will of the operator.

In testimony whereof I affix my signature.

HARRY C. JOHANSEN
